United States Patent Office

Des. 208,431
Patented Aug. 29, 1967

208,431

MOULDER

Walter O. Paulson, Jr., 535 SE. Madison,
Portland, Oreg. 97214

Filed Aug. 19, 1966, Ser. No. 3,539

Term of patent 14 years

(Cl. D55—1)

Fig. 1.

FIG. 1 is a perspective view of the front and left side of the machine; and

FIG. 2 is a perspective view of the rear and right side of the machine.

I claim:

The ornamental design for a moulder, as shown.

References Cited

Modern Plastics, January 1938, page 23, HPM Injection Molding Press.

WALLACE R. BURKE, Primary Examiner.

ALAN P. DOUGLAS, Assistant Examiner.